UNITED STATES PATENT OFFICE.

MYRTON E. REAM, OF CHICAGO, ILLINOIS.

CHILD'S TOILET-SEAT.

1,267,590.

Specification of Letters Patent. Patented May 28, 1918.

Application filed April 24, 1916. Serial No. 93,080.

To all whom it may concern:

Be it known that I, MYRTON E. REAM, a citizen of the United States, residing at Chicago in the county of Cook and State of Illinois, have invented certain new and useful Improvements in Children's Toilet- Seats, of which the following is a specification.

The object of this invention is to provide an improved toilet seat for small children, and the invention aims to provide a seat which may be quickly and securely mounted on a standard toilet seat, which provides a guard device to surround the body of the child and prevent its falling from the seat; and in which the seat-securing means and the said guard means are arranged to be quickly and conveniently collapsed into compact condition for storage or transportation.

In the accompanying drawings, Figures 1 and 2 are perspective views showing a toilet seat embodying my invention, Fig. 1 showing the parts in collapsed position and Fig. 2 showing them in extended or operative position. Fig. 3 is a vertical front-to-rear section, and Fig. 4 is a transverse section showing the seat mounted upon a standard fixture.

In the drawings, 5 indicates a closet bowl and 6 the usual wooden seat thereon. My improved device comprises a base or seat portion 7 having a hole of smaller dimensions than the one in the seat 6. The base 7 is arranged to be secured in place on the seat 6 by means which is secured to the lower side of said base and which depends through the opening in the seat 6 and engages beneath the edges of the latter opening. Said means in the form herein shown comprises a rod 8 having its mid-portion secured to the underside of the base 7 rearwardly of the opening therein in such a manner that the rod may turn in its bearings. Suitable means such as staples 8^a may be employed to secure the rod in place. The end portions of the rod are offset and are sloped downwardly to engage beneath the seat 6. In associating the device with the seat 6 the hooked end portions of the rod 8 are passed through the mid-portion of the opening in the seat 6, the rod 8 being moved by gravity into operative position. The base 7 is then moved rearwardly during which movement the inclined ends of the rod 8 will frictionally bind against the

edge of the opening in the seat 6 so that the base 7 will be firmly secured in place.

Spaced above the base 7 is a guard which may be in the form of a U-shaped frame 9 providing side-arms and a back to partially surround the child. The ends of the frame 9 may be connected by a retainer, such as a detachable flexible strap 10 to complete the inclosure. This guard frame is arranged to be connected to the base 7 by means of two links 11 at opposite sides of said seat near the forward ends thereof, each of said links having its opposite ends pivoted respectively to the seat and the end portions of the frame 9. At the rear of the structure is a link 12 which in this instance is pivoted at its lower end at 13 to the rear edge of the seat 7 and has a notch 14 near its upper end to receive a bolt 15 mounted in the central portion or back of the frame 9. A thumb-nut 16 threaded on the bolt 15 provides means for clamping the link 12 to the frame 9. The rear link 12 swings on an axis at right angles to the axes of the front links 11, so that said front and rear links resist movement of each other and prevent accidental collapse of the guard frame. The rear portion of the frame 9 is preferably spaced forwardly from the rear edge of the base 7 and the link 12 is correspondingly bent forwardly. Due to this bend in the link it will conform to the curved corner of the base 7 when in folded position, as shown in Fig. 1, thereby economizing on space.

In use, the parts occupy the position shown in Figs. 2, 3 and 4. When it is desired to collapse the device for storage, the thumb-nut 16 is loosened and the link 12 is disengaged from the bolt 15 and swung down along the edge of the seat 7, as shown in Fig. 1. The links 11 are then swung rearwardly and the frame 9 is simultaneously swung through an arc of 180 degrees into inverted position, as shown in Fig. 1, so that the frame may be pushed down into close contact with the seat 7. By reason of its inversion the frame 9 is confined within the bounds of the base 7 when collapsed. When the hooked rod 8 is disengaged from the seat 6 the rod may be turned to bring the angular ends closely along the lower face of the seat 7 so as to further reduce the space required for storage of the device. The collapsible feature is a very important one to the manufacturer because it greatly reduces the size of the package to be shipped

and also lessens liability of damage to the parts by rough handling in shipment.

While the preferred embodiment of the invention is shown in the drawings and has been described in detail, I recognize the fact that various modifications may be made without departing from the invention, the scope of which is defined in the appended claims.

10 I claim as my invention:

1. A child's toilet seat comprising a base, a guard-frame, two links pivoted to opposite sides of the base for supporting said frame, and a third link detachably connecting said frame and base.

15 2. A child's toilet seat comprising a base, a U-shaped frame, two links pivotally connecting opposite sides of said base to the ends of said frame, a third link pivoted at its lower end to the rear edge of said base, and means for detachably securing the upper end of said third link to the mid-portion of said frame.

20 3. A child's toilet seat comprising a base, a guard frame spaced above the base, and a plurality of links connecting the base to the frame and allowing the frame to be collapsed downwardly to lie approximately parallel with the base, certain of said links

being mounted to swing at approximately right angles to certain other of the links, whereby accidental collapsing movement thereof is prevented.

4. A child's toilet seat comprising a base, a guard, and means connecting the base and the guard and allowing the guard to be inverted and collapsed downwardly into position close to the base.

5. A child's toilet seat comprising a base, a U-shaped frame spaced above the base, and a plurality of links connecting the base and the frame and arranged to permit the frame to be inverted and pressed downwardly into position close to the upper face of the base.

6. A child's toilet seat comprising a base, a guard spaced above the base, two links pivotally connecting opposite sides of the base to opposite sides of said guard, and a third link detachably connecting the rear portions of the base and the guard, the first mentioned links being arranged to fold rearwardly and downwardly when the third link is disengaged, and the guard being then movable into inverted position to lie close to the base.

In testimony whereof, I have hereunto set my hand.

MYRTON E. REAM.
